UNITED STATES PATENT OFFICE.

MAURICE T. WHITING, OF NEEDHAM, AND EDWARD F. LOGAN, OF LYNN, MASSACHUSETTS, ASSIGNORS TO THE BARRETT COMPANY, OF BOSTON, MASSACHUSETTS, A CORPORATION OF MAINE.

BOTTOM-FILLER FOR BOOTS AND SHOES.

1,263,499

Specification of Letters Patent. Patented Apr. 23, 1918.

Application filed September 22, 1916. Serial No. 121,670.

To all whom it may concern:

Be it known that we, MAURICE T. WHITING and EDWARD F. LOGAN, citizens of the United States, residing at Needham and Lynn, respectively, in the counties of Norfolk and Essex and State of Massachusetts, have invented new and useful Improvements in Bottom-Fillers for Boots and Shoes, of which the following is a specification.

10 This invention relates to improvements in bottom fillers for boots and shoes. More particularly it relates to the means for filling the space in the midst of the sole, between the inner sole and the outer sole and between the edges of the upper which are turned in between these two soles. For filling this space various materials have heretofore been used, such as felt, leather board, and, most commonly at the present time, a 20 pasty compound of cork, sawdust and the like with some cement or other fluid ingredient which permits the whole mass to harden after being pressed into the space. These various devices are used instead of 25 leather because of the stringent necessity of keeping down the cost of finished product. But they have the characteristic defects that they are fragile and friable, and are subject to other objections. Among these other objections are, that when shoes containing felt, paper or "board" fillers are worn in the wet, and moisture has passed through the sole, the filler acts as a sponge or wick which absorbs and holds the moisture there, so that 30 even after the outer sole has dried that part of the sole which is near the wearer's foot remains moist because of the dampness retained in the filler. The same is true when leather skivings are used. It is true that 35 40 paste fillings may embody materials that are more or less waterproof, but they also embody materials which are more or less soluble, or which crack so as to permit the passage of moisture, or which, if not hard enough to be brittle, are sufficiently soft and fluid so that under the heat of the wearer's foot and the repeated flexure which they undergo, they lose their proper form and compact themselves into places between the soles 45 50 where the pressure is least, making hollows and bunches which are disagreeable and even painful as well as causing shortening of the life of the shoe.

The present invention accomplishes the

triple purpose of providing a filler which 51 durably retains its flexibility without shifting its form or position in the sole; of being waterproof and permanently non-absorbent, while being flexible and becoming neither 56 brittle nor crumbly; and of being relatively 60 low in cost. These objects are accomplished by providing a sheet of felt of suitable thickness, depending upon the thickness of the space to be filled; saturating the same with 65 bituminous material of such a quality of 70 softness as is permanently flexible at ordinary temperatures, notwithstanding the thickness of the mass; coating both sides of 75 this saturated felt with a layer of bituminous material of a sufficient degree of tenacity, so that it constitutes a cover or flexible shell holding the softer bituminous material in place among the fibers of the felt; and cutting this composite sheet by dies into 80 pieces of the proper shape and size to fit approximately the said spaces within the bottoms of shoes. The operation of cutting can be performed through a number of thicknesses of the sheets at once. As the manufacture of the sheet can be carried out by 85 machinery which is practically automatic, the elements of cost in manufacture are extremely low so far as labor is concerned; and as the cut pieces can be made so as to fit pretty accurately the space in the shoe bottom, the cost of labor of inserting one is 90 practically negligible. An embodiment of the invention is illustrated in the accompanying drawing, in which,

Figure 1 is a plan of filler;

Fig. 2 is a side elevation thereof, with thicknesses exaggerated for the sake of clearness; and

Fig. 3 shows the filler arranged in a shoe. Referring to the drawings, the commingled bituminous material and felted fibers are seen conventionally indicated at 95 10; and confining layers of harder bituminous material, adhering to the fibrous and to the interior bituminous material are 100 marked 11 and 12. In the process of manufacture of the filler, a web of felt or suitable similar material is passed through a bath of molten bituminous material of such 105 quality and temperature that in the bath it is sufficiently liquid to penetrate thoroughly and to saturate the web of felt and yet to solidify therein upon the emergence of the

web from the bath. As is well known, bituminous materials have a considerable range of hardness at ordinary atmospheric temperatures, according to their various sources and compositions. It is desirable, for the purpose of the invention, that a bituminous material be chosen for saturating combination with the felt which is sufficiently stiff to take and hold a firm grip on the fibers of the felt which it surrounds so thoroughly, and yet which is sufficiently mobile to be capable of being bent repeatedly without breaking as its fibers bend with each step of the wearer of the shoes. It results from this, when the further stages of the process have been carried out, that the greater portion of the filler is a bed of felt, flexible when subjected to bending stresses and so compressible as to have in some degree the qualities of a cushion, but not extensible in the direction of its length or breadth, because of the entanglement of the fibers with each other and because of the cementing and obstructing action of the bituminous solid filling in the spaces between the fibers. The interlacing of the fibers within the felt stops it from expanding materially in thickness. The web which has been through the saturating bath, and whose absorbed contents is cooled and solidified may then be passed through compressing rollers where a layer of heated liquid bituminous material is spread over it of such quality as solidifies when it cools, into a skin having a distinct quality of tenacity. The heat of this material, when it is applied as a molten layer, softens the surface part of the bituminous material in the saturated web, and, these two bituminous materials flow together and make a joint or union which is analogous to welded joints of metals. At the same time the added molten material becomes attached to those fibers of the felt which are at the surface of the web. The compressing roller may give this material any superficial form desired, either a smooth surface or a surface with diamond shaped or pebbly elevations, or a surface having any other characteristic, it being understood that no great difference of elevation is referred to but only enough to be manifest to the eye and touch, and to provide a slightly rough surface. The other side of the web may be likewise coated with a layer of the harder bituminous material. The web is then ready to be cut into pieces of the desired shape and size to fill the spaces in the boot or shoe bottoms. This cutting may be accomplished by dies acting upon sheets several folds thick.

The finished product has the general characteristic of a sheet cushion protected by a tough skin of bituminous material which is connected integrally to the softer, less tough and somewhat more flexible in-

terior of bituminous material and is attached also to the surface fibers of the web. Hence the product as a whole is a composite sheet in which the parts are firmly held together by inherent characteristics, without the aid of glue or the like and without either the initial cost of glue or the subsequent danger of its softening or of its stiffening and becoming brittle. Moisture cannot penetrate the material nor can it work its way in between the various layers composing it. Inasmuch as the filler is ordinarily only an approximate fit for the space left by the turned edges of the upper, it does not absolutely prevent the passage of water through the sole of the boot or shoe; but this is an objection of no consequence, for even if it were entirely to fill that space moisture might still pass through the leather immediately outside of the filler; but it has the great advantage that it does not absorb and hold any moisture that enters through the leather, and also that it prevents passage of moisture through the middle part of the sole. While its surface may be either rough or smooth at pleasure, it is thought by some that in usage it wears into a better fit when its surface is originally a little rough. In any event however, it prevents the development of a squeak in the sole, such as frequently arises from friction when fillers of other type are used. This is partly because it never becomes hard and brittle and partly because it can adapt itself somewhat to the adjacent curvature and surfaces of outer or inner sole and can yield more or less under the stresses imposed upon it when the shoe is bent.

Fillers made according to the invention are particularly useful in connection with light weight boots and shoes, either of Good-year welt style or those which are flexible MacKay sewed. When so placed it provides a cushion filler which backs up the outer sole in such a way that thin material can be used for it, and also thin material for the inner sole, without the sole as a whole seeming to lack substance and without the outer sole wearing through any more rapidly than it would do naturally, according to its quality and thickness, being in this respect unlike the fillers made which are in such general use today consisting of cork dust, sawdust, rosin, wax tailings, and the like, which crumble and then roll forward into the toe and backward into the shank leaving the sole subject to unequal stresses and causing it to wear out earlier than it should. Furthermore it is free from objections, which are important from the standpoint of shoe manufacturers, in that its use by them requires no steam heated kettles or inflammable materials that can only be used hot, or with danger of fire from spontaneous combustion, or which occasionally cause

dark stains on the finished bottoms. While the particular form of the invention described is deemed preferable, it will be obvious that variations may be made.

5 We claim:—

1. The combination, in a shoe, of an inner sole, an outer sole, and a flexible, composite and strongly coherent body separating them, comprising a layer of felt impregnated with 10 bituminous material and a layer of tough bituminous material constituting a facing for and fused to the said impregnating bituminous material.
2. The combination, in a shoe, of an inner sole, an outer sole, and a flexible, composite and strongly coherent cushion separating them, having interiorly felt and a relatively soft bituminous material impregnating the felt, and having exteriorly a tough and relatively hard bituminous layer fused to the 20 impregnated bituminous material.
3. The combination, in a shoe, of an inner

sole, an outer sole, and an intervening composite body having a layer of combined felt and bituminous material and filmy layers 25 of material of relatively great tenacity adhering to each side thereof and exposed to rubbing on flexure of the soles.

4. The combination, in a shoe, of an inner sole, an outer sole, and an intervening stratified body having an interior layer of combined felt and bituminous material and having exterior bituminous layers adhering 30 strongly thereto but not to the adjacent soles, and being of a high degree of density 35 and tenacity such as may result from compression of the strata together.

Signed by us at Boston, Mass., this 16th day of September, 1916.
